Inventor:
Ralph E. Williams,
By James T. Bunker
his attorney.

UNITED STATES PATENT OFFICE.

RALPH E. WILLIAMS, OF LOS ANGELES, CALIFORNIA.

SPOTLAMP.

Application filed April 7, 1920. Serial No. 372,043.

To all whom it may concern:

Be it known that I, RALPH E. WILLIAMS, a citizen of the United States, residing at Los Angeles, in the county of Los Angeles, State of California, have invented new and useful Improvements in Spotlamps, of which the following is a specification.

This invention relates to lamps and more specifically to spotlamps such as are used in connection with automobiles and the like. An object of the invention is to provide a lamp of this character which is sightly, simple, effective, and inexpensive to manufacture.

15 A particular and noteworthy feature of the invention is the extremely simple, effective, and sightly construction of the lamp. The construction although extremely simple is strong, durable and water-tight so that 20 the lamp can be exposed to rain or severe weather without danger of water getting into it to short circuit the electrical connections, etc.

Further objects and features of the invention are set forth in the following specification wherein I describe a typical embodiment of the invention and throughout which reference is had to the accompanying drawings, in which—

30 Fig. 1 is a longitudinal sectional view of a lamp embodying the present invention; Fig. 2 is an enlarged detail sectional view of the rear portion of the lamp; Fig. 3 is a transverse detail sectional view taken as indicated by line 3—3 on Fig. 2.

Throughout the drawings the numeral 10 designates the lamp which is carried on a bracket 11. The lamp 10 comprises a cylindrical casing 31 at the forward end of which 40 is a flange 32, which carries reflector 33, and over the rear end of which is carried, or extends, a cap 34. The cylindrical casing 31 is preferably cast or formed integral with the flange 32 and has arranged in it an electrical connector 35 which carries and connects the bulb 36, arranged within the reflector 33, with the plug 37 carried in the cap 34. The plug 37 which is carried in the cap 34 is connected with lead wires 38.

50 The electrical connector 35 comprises a metal sleeve 39 which is slidably carried in

the casing 31 and in which is arranged a core 40 of insulating material. Contacts 41 extend longitudinally through the core 40. The inner or forward end of the sleeve 39 55 forms a socket 42 which carries the base 43 of bulb 36. The other end of the sleeve 39 is somewhat enlarged, in fact it is enlarged so that its outside diameter is the same as the outside diameter of the casing 31, to form 60 a socket 46 which is adapted to receive and removably hold the plug 37. The plug 37 is screw threaded into the cap 34 and has formed in it a groove 44 which co-operates with a projection 45 formed in and project- 65 ing from the wall of socket 46. The groove 44 and projection 45 co-operate to allow the plug 37 to be rotated in the socket 46 to make or break the electrical connection be- 70 tween the lead wires 38 and the contacts 41, or bulb 36, without causing it to be brought to a position where it can be, or is liable to be, withdrawn from the socket. It will be readily understood how the plug 37 may be rotated or manipulated by the cap 34 so 75 as to cause the contacts 47 in the plug 37 to be in line, or engagement, with the contacts 41 in core 40, or so as to be out of engage- 80 ment with the contacts 41 in the core 40, as desired. The particular form of plug and 85 socket herein shown and described is the subject matter of a co-pending application of Henry H. Moreton, entitled "Electrical connector" Serial No. 371,856 filed April 7, 1920.

The cap 34 which carries the plug 37 is preferably a metal cap having a suitable knurled, or handle forming, portion 50 by which it may be manipulated or rotated to cause manipulation or rotation of the plug 90 37. The cap 34 forms a cylindrical sleeve 51 which extends or fits, over the exterior of the socket 46 and also the rear portion of the casing 31. The cylindrical sleeve portion 51 of the cap 34 preferably fits the socket 46 95 and end portion of casing 31 fairly accurately, or tightly being only sufficiently loose to allow proper operation or manipulation of the cap. The sleeve 51 in extending over the socket 46 and the rear end portion of 100 the casing 31 not only makes the lamp sightly and neat in appearance but also

— renders it practically water-tight. Further the space between the end of the casing 31 and the socket 46 is filled by a suitable washer 60 which positively checks the flow 5 of water into the interior of the light. It will be readily understood how any water, that passes between the outer wall of the rear end portion of the casing 31 and the inner wall of the sleeve 51, engages the 10 washer 60 and is prevented from passing any further into the light. Although water is free to get into the rear portion 62, of the cap 34, through the hole 65, in which lead wires 38 and spring 66 are carried, it can not get 15 past the rear portion of the plug 37 due to the plug being tightly screw threaded in the cap 34 and the contacts being tightly carried in the plug. The spring 66, which is carried in the rear portion 62 of the cap 20 34 so as to extend through the hole or aperture 65 and rearwardly from the cap 34, is to protect the lead wires 38 and prevent them from being broken off at the cap.

The flange 32, which is formed at the end 25 of the casing 31 and to which the reflector 33 is secured, conforms with the curvature of the reflector 33. The reflector 33 is preferably soldered or otherwise tightly connected or secured to the flange 67. A set screw 69 extends through an enlarged portion 68 of the casing 31 and engages the sleeve 39 to set or lock it in any desired position in the casing 31. The sleeve 39 being slidably carried in the casing 31 may be moved longitudinally therein, in order to properly focus or arrange the bulb 36 relative to the reflector 33, and may be set in the proper position by the set screw 69. In practice the flange 32 is preferably cast flat and is subsequently stamped or pressed to have the proper curvature or configuration.

In the particular lamp shown in the drawings the light 10 is connected to the bracket 11 by suitable screws 70 which connect the arm 20, of the bracket 11, with the arm 71, which extends from the flange 32. The arm 71 is preferably formed integral with the flange 32 and is comparatively broad and flat, as shown in Figs. 1 and 2 of the drawings. The arm 20 of the bracket 11 is also comparatively broad and flat and is shaped to register, or conform, with the shape of the arm 71. In the particular construction shown in the drawings there are three screws 50 55 70 provided to connect the arms 20 and 71, there being one screw arranged near the flange 32 and two at the outer portion of the arm 71, as clearly shown in Fig. 1 of the drawings. The screws 70, in connecting the arm 20 and 71, extend through bores 72 in the arm 20 and screw thread into screw threaded bores 73 in the arm 71. There are preferably annular wedge shaped projections 74 on the arm 71 at the bores 73 60 65 which engage similarly shaped recesses 75

in the arm 20 at the bores 72, as clearly shown in Figs. 3 and 5 of the drawings. The projections 74 and recesses 75 co-operate to relieve shearing strains from the screws 70 and cause the screws 70 to act merely as 70 clamping members, or so as to hold the two arms together.

It is to be noted that the lamp provided by the invention requires very little machine work for manufacture of parts and assembly. The flange and casing are formed practically entirely without machine work, the flange being pressed to shape and the interior of the casing being brought to proper size by broaching. The assembled reflector, flange and casing are enameled or otherwise finished to suit. The connection between the lamp and bracket requires only the drilling and topping of the screw holes. The parts of the connector are drawn from 80 tubing; and the cap 34 may be cast or pressed or drawn.

Having set forth only a preferred embodiment of my invention I do not wish to limit or restrict myself to the details hereinabove 90 set forth but wish to reserve to myself any changes or modifications that may appear to those skilled in the art or that may fall within the scope of the following claims.

Having described a preferred form of my 95 invention, I claim:

1. In a lamp of the character described, a cylindrical casing, an electrical connector arranged in the casing, a socket formed at the rear end of the electrical connector and extended beyond the rear end of the casing, the socket extension comprising a cylindrical wall the same size as the casing, a cap, a plug carried in the cap and adapted to extend into and co-operate with the socket, and a cylindrical sleeve extending from the cap to slidably fit over and cover the socket and the rear end of the casing.

2. In a lamp of the character described, a casing, an electrical connector carried in the casing, a socket formed at the rear end of the electrical connector and extended beyond the rear end of the casing, the socket extension being the same size as the casing and arranged relative to the casing so that there is a space between it and the rear end of the casing, a washer arranged in said space, a cap adapted to cover the rear end of the casing, the washer, and the socket, and a plug carried in the cap and adapted to co-operate with the socket.

3. A lamp of the character described comprising, a cylindrical casing, a flange formed at the front end of the casing, a reflector mounted on the flange, an electrical connector carried in the casing, a socket formed at the rear end of the electrical connector and extended beyond the rear end of the casing, the socket extension being the same size as the casing and spaced from the cas-

ing so that there is a space between the rear end of the casing and the socket, a washer arranged in said space, a cap, a plug carried in the cap to co-operate with the socket, 5 and a sleeve formed on the cap to extend over and cover the socket, the washer, and the rear portion of the casing.

In witness that I claim the foregoing I have hereunto subscribed my name this 24th day of March, 1920.

RALPH E. WILLIAMS.

Witness:

VIRGINIA BERNER.
